ARMATURE RECUTTING TOOL

Walter H. Rhindress, Braintree, Mass.

Application August 2, 1940, Serial No. 349,905

9 Claims. (Cl. 82—4)

This invention relates to tools for cutting or recutting such armatures as are carried by a shaft. Its purpose is to cut the curved face of an armature commutator to form a perfect cylinder, the axis of which is the center of the shaft.

This is mainly a hand tool and its purpose is to provide means by which the armature is held on its shaft and revolved against a cutter with sufficient force to be cut but to permit the tool to be easily operated by hand and at the same time to cause the armature to move axially a little for each cut. The revolving and feeding can be accomplished by using a very fine thread but when the spiral cut is finished and the parts must be returned to their original position to receive another armature, the fine thread requires a great many turns, meaning delay and extra work. Besides this, a fine thread is not strong and such a tool requires strength.

This tool is so arranged that while the armature is moving against the cutter and being cut, its axial progress is slow, but when it is desired to return the parts to their original position, it can be done very quickly by a relatively few turns of a feed screw having a relatively coarse thread.

The turning of the armature for the cutting is steady, but the axial feed is intermittent while cutting but steady on return.

I am aware that an armature on a shaft can be cut by holding the shaft in a lathe chuck on a horizontal axis and by either moving a cutter along it while the armature is being revolved or feeding the armature toward or along a stationary cutter.

I am aware that in patent to Burrows and to myself dated January 23, 1940, No. 2,187,874, the armature is held in a vice while a hand tool is fixed to the armature shaft and the tool with a cutter is revolved and moved forward by a hand wheel. With any construction where either the tool or the armature is suspended on a horizontal axis, there is a tendency to sag and when either is revolved against a cutter, the cut is not a true circle and with a direct hand drive with a hand tool, there is a tendency to bear down at certain parts of the rotation and this also prevents the cut from being a true circle. There is also a limit to the effective working pressure which can be manually applied and as this is a hand tool for cutting metal, there is a limit to the width and depth of the cut which can be made without the use of power.

With this tool, the armature and shaft are carried vertically thus avoiding any tendency to

sag, and the pressure is applied by a hand wheel on a horizontal axis which prevents sagging and uneven pressure on the revolving armature which is being cut. The cutting element is stationary and although the feed screw has a relatively coarse pitch, the actual movement of the armature is intermittent, the principal part of the cutting being annular rather than spiral. This permits the use of a strong, coarse feed screw to cut a thin or narrow chip and of course such a chip can be cut with less manual effort than a thick wide chip.

In the drawings

Fig. 1 is an isometric view of my tool in the upright position, as it is preferably used, and with the armature and shaft as they appear at the end of a cut.

Fig. 2 is an isometric view similar to Fig. 1 but from a different direction and with the parts as they appear at the beginning of a cut.

Fig. 3 is a vertical sectional view as on the line 3—3 of Fig. 4.

Fig. 4 is a plan view of the tool without the armature and shaft.

Fig. 5 is a horizontal sectional view as on the line 5—5 of Fig. 3.

Fig. 6 is a horizontal sectional view as on the line 6—6 of Fig. 3.

Fig. 7 is a side elevation of a preferred type 30 of cutter assembly in one position and Fig. 8 is a similar view showing it in a different position.

Fig. 9 is a detail view of another cutter assembly.

Fig. 10 is an enlarged elevation of the spindle with the collet and drawbar, removed from the machine, with parts broken away to show the construction.

In the drawings, A represents the body of the 40 device from which extends a projection 39 by which the whole tool can be held in the jaws of a vice V. As shown, it is held vertically.

Extending preferably vertically through body A is a spindle hole 40 for the tubular spindle 45 B. Extending lengthwise on the outside of this spindle B is a turning slot 41 into which enters a turning pin 47 which extends inward from the pinion J driven by drive gear K and a handle L.

On the outside at one end of spindle B is the 50 annular feed groove 44 in which are one or two pins, such as 61, which engage a Geneva motion to be described.

Slidable in the hole 46 in spindle B is a collet C having at the top a split end 30 to receive the 55 shaft 31 of the armature 32 and provided with

threads 33 at the other end. Drawbar D has threads 34 which engage with the threads 33 on the collet C and has an integral collar 35 which extends over and rests against the bottom outside end 45 of spindle B. This collar 35 has turning slots 36, 36 by which it and drawbar D can be turned or held stationary as by a pin P. When not so held, collet C and drawbar D move with spindle B, but when held by pin P, threads 33 and 34 cause them to move towards or away from each other depending on the direction in which L, K, J and B are turned to engage and hold or release the shaft 31 of the armature 32.

There is a cutting assembly attached to the body A including a cutter H, rocker bar I and adjusting screw G by which the depth of the cut on the armature can be regulated.

The commutator 20 of armature R is carried by shaft 31 and includes metal strips 21, 21 and insulation 22, 22.

Cutter holding block 90 is slidable in body A and can be adjusted by set screws 93, 93.

Pin 38 in spindle B enters keyway 37 in collet C. Rocker bar I and cutter H extend sufficiently up and out beyond the end of spindle B so that the armature can be started at the high point shown in Fig. 2 and brought down to the dotted position, thereby allowing the cutter to cut over the entire curved surface.

The slow cutting, feeding and quick return are accomplished by a feed screw O which is revolvable, but not axially movable, in body A and is turnable by a small hand crank 60. It is held in place by a collar 66 and nut N.

M represents a combination feed gear and Geneva motion which is threaded on the inside 62 to engage the outside threads 63 on the feed screw O. The Geneva wheel 64 fits into the annular feed groove 44 on the spindle B in such a way that it is engaged by one or more of the Geneva pins 61, as the spindle B is turned by the pin 47 carried by the pinion J.

As the combination feed gear and Geneva motion are turned, they are carried along the feed screw O and carry with them the spindle B, collet C, drawbar D, armature R and its shaft 31. The axial movement is intermittent as the Geneva pin 61, operates on the Geneva wheel, and the cutting is not a continuous spiral.

When the cutting of one armature has been accomplished, the crank 60 of the feed screw O is turned in the opposite direction and as the threads on the feed screw are of a relatively coarse pitch, each turn moves the spindle B and its accompanying parts a very much greater distance back than the distance in the opposite direction produced by each turn of the handle L. This ratio can be changed to make it greater or less.

Parts B, C and D move together except when pin P is held in a slot 36 when gripping and releasing a shaft 31.

As a convenient arrangement for seizing and holding the shaft 31 of an armature R, I use a pin P normally kept out of turning slots 36, 36. When it is desirable to open or close the end 30 of the collet C, this pin P is pressed in to engage a slot 36 and this stops drawbar D from turning. Therefore, when handle L, gear K and pinion J are turned, spindle B and the Geneva motion M are turned thus moving spindle B forward or back thereby opening or closing the split end 30 of collet C on the shaft 31. First the collet is opened, then the shaft is inserted, then the collet is closed and then pin P is allowed to

spring out whereupon the parts are ready to operate.

When the pin P does not engage either slot 36, the turning of handle L moves the spindle B and collet C forward or back slowly as these advance only when the Geneva wheel 64 is moved by a pin 61. As shown, it requires five engagements of a pin 61 to advance the parts one thread on feed screw O. On the other hand, when turning feed screw O by crank 60, the action is five times as rapid and the spindle and collet can be moved forward or back very quickly.

In practice, after the armature and shaft have been gripped, these parts are advanced to the forward position by turning crank 60 and are drawn back by turning the handle L.

One advantage of this construction is that when the Geneva motion has been carried back as far as the collar 66 on the feed screw O, all the parts revolve together thus automatically stopping the device and preventing cutting too far on the armature commutator.

Nut N overlaps collar 35 and holds drawbar D up allowing collet C to turn and move up on pin 38, when pin P engages a slot 36, to open split end 30.

In repairing armature commutators in addition to turning the curved surface down to a true cylinder, it is often necessary or desirable to undercut the isinglass or other insulation 22, 22 between the metal strips 21, 21, and it is desirable that this should be done accurately and while the armature is held in position so that the cuts will be parallel with the axis.

This is conveniently done by using a special combination cutting assembly such as is shown at T in Figs. 7 and 8. This can be used with a cutter such as H for turning down the armature or for undercutting by substituting for H, a cutter 74 of a different shape.

A block 70, preferably, with a straight direction groove 72 is slidable in ways 71, 71, in a direction exactly parallel with the axis of the work. Block 70 can be moved parallel with the axis or clamped in position by the set screws, 73, 73.

Through block 70 is a rectangular guideway 80 for a cutter carrying slide bar 81 which fits snugly on each side but has clearance at the top and bottom. This slide bar 81 has a recess 82 in which a cutter like 74 or like H can be clamped in adjusted position by a set screw 83. An undercutter such as 74 is preferably of a different shape from a cutter like H and preferably has a plurality of teeth.

A handle 86 is pivoted at 85 to the cutter carrying slide bar 81 and at 87 to a link 88 which at 89 is pivoted to the block 70. There is also a set screw 76 through block 70 which can be tightened so as to hold the slide bar 81 rigidly in place when the commutator face is being turned. When undercutting, this set screw 76 is loosened, allowing the cutter carrying slide bar 81 to move to and from the axis of the armature so that by pressing on the handle 86 on the forward stroke, the cutter 74 will cut and by lifting handle 86 with the link 88 as shown in Fig. 8, the cutter 74 and the cutter bar 81 can be brought back for the next cut. In this under-cutting operation, the armature and commutator can be moved by the handle L so that an insulation strip 22 will be opposite the cutter 74.

As shown in Fig. 9, a cutter such as H or 74, can pass through a groove 91 in a block 92 and can be adjusted by means of a collar 94, screws 95 and 96 and nut 97.

I claim:

1. In a machine for cutting commutators of armatures which are provided with a shaft; the combination of a body, including means to hold the body stationary and a spindle bearing hole; with a tubular spindle axially slideable in the spindle bearing hole, such spindle being formed with an outside longitudinal spindle turning slot and an annular feed groove in which is a Geneva pin; spindle driving means including a turning pin in the spindle turning slot; work holding means extending through the spindle including a split collet with jaws at one end to receive and hold the armature shaft and at the other end a drawbar threaded to the collet to open and close such jaws; a spring actuated pin to stop the drawbar from turning with the collet; a Geneva wheel which enters the feed groove in the spindle and engages the Geneva pin therein and is provided with a threaded feed screw passage; a feed screw with an outside handle revolute in the body and which passes through and engages the threads of the Geneva wheel feed screw passage; and a cutter assembly adjustably attached to the body in position to engage an armature commutator as it is revolved and moved by the spindle and to be moved along the surface of the commutator parallel with its axis.
2. In a machine for cutting commutators of armatures which are provided with a shaft; the combination of a body, including means to hold the body stationary and a spindle bearing hole; with a tubular spindle axially slideable in the spindle bearing hole, such spindle being formed with an outside longitudinal spindle turning slot and an annular feed groove in which is a Geneva pin; spindle driving means including a turning pin in the spindle turning slot; work holding means extending through the spindle including a split collet with jaws at one end to receive and hold the armature shaft and at the other end a drawbar threaded to the collet to open and close such jaws; a spring actuated pin to stop the drawbar from turning with the collet; a Geneva wheel which enters the feed groove in the spindle and engages the Geneva pin therein and is provided with a threaded feed screw passage; a feed screw with an outside handle revolute in the body and which passes through and engages the threads of the Geneva wheel feed screw passage; and a cutter assembly adjustably attached to the body in position to engage an armature commutator as it is revolved and moved by the spindle.
3. In a machine for cutting commutators of armatures which are provided with a shaft; the combination of a body, including means to hold the body stationary and a spindle bearing hole; with a tubular spindle axially slideable in the spindle bearing hole, such spindle being formed with an outside longitudinal spindle turning slot and an annular feed groove in which is a Geneva pin; spindle driving means including a turning pin in the spindle turning slot; work holding means carried by the spindle to receive and hold the armature shaft; a Geneva wheel which enters the feed groove in the spindle and engages the Geneva pin therein and is provided with a threaded feed screw passage; a feed screw which passes through and engages the threads of the Geneva wheel feed screw passage; and a cutter assembly adjustably attached to the body in position to engage an armature commutator as it is revolved and moved by the spindle and to be moved along the surface of the commutator parallel with its axis.
4. In a machine for cutting commutators of armatures which are provided with a shaft; the combination of a body including means to hold the body stationary, a spindle bearing hole and a guideway parallel with the axis of the spindle bearing hole; with a tubular spindle revolute and axially movable with a feed gear, in such bearing hole; manually operable spindle driving means for turning the spindle rapidly and moving it axially slowly with the feed gear; other manually operable means including a feed screw for the feed gear to move the spindle axially rapidly; work holding means carried by the spindle to receive and hold the armature shaft; and a cutter holding block slideable in the guideway parallel with the axis of the spindle, and means to hold the block in fixed position in the guideway.
5. In a machine for cutting commutators of armatures which are provided with a shaft; the combination of a body including means to hold the body stationary, a spindle bearing hole and a guideway parallel with the axis of the spindle bearing hole; with a spindle revolute and axially movable with a feed gear, in such bearing hole; spindle driving means for turning the spindle and moving it axially with the feed gear; other means including a feed screw for the feed gear to move the spindle axially; work holding means carried by the spindle to receive and hold the armature shaft; and a cutter holding block slideable in the guideway parallel with the axis of the spindle, and means to hold the block in fixed position in the guideway.
6. In a machine for cutting commutators of armatures which are provided with a shaft; the combination of a body including means to hold the body stationary, and a spindle bearing hole; with a spindle revolute and axially movable with a feed gear, in such bearing hole; spindle driving means for turning the spindle and moving it axially with the feed gear; other means including a feed screw for the feed gear to move the spindle axially; work holding means carried by the spindle to receive and hold the armature shaft; and a cutter holding block carried by the body.
7. In a tool for cutting commutators of armatures which are provided with a shaft; the combination of a body including means to hold the body stationary in a vertical position, a spindle bearing hole and a cutter holding guideway parallel with the axis of the spindle bearing hole both in a vertical position; with a tubular spindle revolute and axially movable in such spindle bearing hole; work holding means carried by the spindle to receive and to hold the armature shaft; manually operable means for turning the spindle; a manually operable feed screw turnable in the body and having outside threads; means including a feed gear threaded on the inside to engage the outside threads on the feed screw; connections between the feed gear and the spindle for moving the feed gear and spindle when the feed screw is turned and for turning the feed gear intermittently on the feed screw when the spindle is turned whereby the feed gear is revolved more slowly than the spindle as the spindle is being turned and whereby the feed gear and the spindle can be retracted slowly by turning the spindle and can be advanced rapidly by turning the feed screw; and a cutter holding block slideable in the guideway parallel with the axis of the spindle and including means to hold the block.

in fixed position in the cutter holding guideway.

8. In a tool for cutting commutators of armatures which are provided with a shaft; the combination of a body including means to hold the body stationary, a spindle bearing hole and a cutter holding guideway parallel with the axis of the spindle bearing hole; with a tubular spindle revoluble and axially movable in such spindle bearing hole; work holding means carried by the spindle to receive and to hold the armature shaft; manually operable means for turning the spindle; a manually operable feed screw turnable in the body and having outside threads; means including a feed gear threaded on the inside to engage the outside threads on the feed screw; connections between the feed gear and the spindle for moving the feed gear and spindle when the feed screw is turned and for turning the feed gear on the feed screw when the spindle is turned whereby the feed gear is revolved more slowly than the spindle as the spindle is being turned and whereby the feed gear and the spindle can be retracted slowly by turning the spindle and can be advanced rapidly by turning the feed screw; and a cutter holding block slidable in the guideway parallel with the axis of the spindle and in-

cluding means to hold the block in fixed position in the cutter holding guideway.

9. In a tool for cutting commutators of armatures which are provided with a shaft; the combination of a body including means to hold the body stationary and a spindle bearing hole; with a tubular spindle revoluble and axially movable in such spindle bearing hole; work holding means carried by the spindle to receive and to hold the armature shaft; manually operable means for turning the spindle; a manually operable feed screw turnable in the body and having outside threads; means including a feed gear threaded on the inside to engage the outside threads on the feed screw; and connections between the feed gear and the spindle for moving the feed gear and spindle when the feed screw is turned and for turning the feed gear on the feed screw when the spindle is turned whereby the feed gear is revolved more slowly than the spindle as the spindle is being turned and whereby the feed gear and the spindle can be retracted slowly by turning the spindle and can be advanced rapidly by turning the feed screw.

WALTER H. RHINDRESS.
